(57) **CLAIM**

I claim the ornamental design for a V-shaped soft side mah jongg set bag, as shown and described.

DESCRIPTION

FIG. 1 is a perspective view of a V-shaped soft side mah jongg set bag embodying my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 6 Drawing Sheets
